Des. 184,738
Patented Mar. 31, 1959

184,738

TOY CRADLE OR SIMILAR ARTICLE

Gilbert Josephson, White Plains, N.Y.

Application November 12, 1957, Serial No. 48,427

Term of patent 14 years

(Cl. D34—15)

Fig. 1 is a perspective view of a toy cradle showing my new design;

Fig. 2 is a front elevational view, to a reduced scale;

Fig. 3 is a rear elevational view, to a reduced scale; and

Fig. 4 is a side elevational view, to a reduced scale, the opposite side being substantially a mirror image thereof.

I claim:

The ornamental design for a toy cradle or similar article, substantially as shown and described.
